UNITED STATES PATENT OFFICE.

ADOLF STEFFEN, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

DESIGN FOR AN ELECTRIC PORTABLE LIGHTING FIXTURE.

61,427.

Specification for Design. Patented Aug. 29, 1922.

Application filed October 17, 1921. Serial No. 508,387. Term of patent 3½ years.

To all whom it may concern:

Be it known that I, ADOLF STEFFEN, a citizen of the United States, residing at Pittsburgh, in the county of Allegheny and State of Pennsylvania, have invented a new, original, and ornamental Design for an Electric Portable Lighting Fixture, of which the following is a specification, reference being had to the accompanying drawing, forming part thereof.

The figure is a perspective view showing my new design.

I claim:

The ornamental design for an electric portable lighting fixture, as shown.

ADOLF STEFFEN.
